SHIRT IRONING MACHINE

Andrew Vargo, Bridgeport, Conn., assignor to
Edward H. Liefeld, Bridgeport, Conn.

Application August 31, 1931, Serial No. 560,350
Renewed March 9, 1934

5 Claims. (Cl. 68—9)

This invention relates in general to ironing machines, and more particularly, to improvements in a shirt bosom ironing machine which serve to protect the free ends of collars and other parts of the shirt from improper wrinkling and creasing.

In machines for ironing shirt bosoms it is desirable to iron as close to the neckband as possible without crushing the band, and it is especially desirable to iron without creasing the bosom and crushing the collar of shirts of the collar attached type.

It is customary to provide a neckband form and clamping device on ironing machines which 15 serves to hold neckbands of shirts in a predetermined position during ironing, and it has heretofore been proposed to provide small vertically disposed pins or other projections on the neckband form for protecting the free ends of collars.

20 However, in these previous proposals it was necessary to perform several separate operations each time a shirt with a collar attached was ironed. In particular, it was necessary to turn in and turn back first one and then the other of the free 25 ends or points of the collars in back of the pins or other projections. These were slow, time-consuming operations which, if not done carefully, would result sometimes in crushing or improperly creasing the collar.

30 The difficulty is not that the engagement of the heated plate would do any damage to the collar but rather that if the collar ends should be caught between the two plates it would be given a crease or fold where these are not wanted. This crease 35 or fold cannot be ironed out by merely placing it in the collar ironing machine for it requires practically rewetting the collar and unavoidably the bosom in order to take out the crease.

It is an object of the present invention to 40 provide a device or arrangement for protecting the free ends or points of collars during the bosom ironing operation and especially to provide a device of this type which requires less time to operate, and one which is simpler and more 45 efficient than those heretofore proposed. With this object in view, the present invention provides a safety shield preferably made integral with a neckband clamping device, adapted to sweep 50 across the bosom a short distance toward the neckband and to automatically, without manual manipulation of the collar or its ends, move the collar ends to a safe, out-of-the-way position and maintain them there during the bosom ironing 55 operation.

Other objects and advantages will hereinafter appear.

In the drawings—

Figure 1 is a front elevation of the main operating parts of a shirt ironing machine embodying the present invention.

Fig. 2 is a top plan view of the neckband clamping device and safety shield of the present invention in its intermediate position.

Fig. 3 is a view similar to Fig. 2, but shows the 65 parts in the final or clamping position.

Fig. 4 is a view looking at the front of the neckband clamping device and collar safety shield of the present invention in its full operative position.

70 In the drawings there is shown a shirt ironing machine comprising a base 10 with vertical standards (not shown) supporting a combined steam table stationary platen 11. Above the platen and mounted upon suitable supports for 75 either vertical or oscillating movement into operating or ironing engagement with the platen is a movable presser 12. Preferably, the platen is provided with a large convex upper surface 13 cushioned, and fabric covered, and the movable 80 presser is provided with a concave lower surface 14 of highly polished uncovered metal, the general arrangement being such that steam heat and pressure may be applied by the mating surfaces 13 and 14 to a shirt or other article placed there- 85 between, in the now well-known manner.

To iron partially closed front shirts, that type 90 wherein a small gap and only one or two buttons are provided beneath the neckband for pulling the shirt over the user's head, the shirt is passed onto the stationary platen by pulling it over the head end 15 of the platen. In the case of ironing coat-type shirts which are open entirely down the front it is merely necessary to wrap the shirt 95 around the platen until the edges of the split portion are adjacent each other or they may be overlapped and one or two buttons secured in the buttonholes.

To properly locate and maintain the shirt on the platen, to prevent unnecessary wrinkling of 100 the bosom, and to protect the neckband from being crushed by the movable presser 12, a neckband form 16 is provided on the head end 15 of the platen 11, and projects slightly above the top surface thereof to accommodate various size 105 neckbands.

Preferably, the form 16 is made slightly smaller than the smallest neckband normally placed thereon, as shown in Figs. 1, 2 and 3, so that it is possible to have the neckband buttoned to- 110

gether at the time of pressing or have them separated if desired, as shown in Figs. 3 and 4, particularly.

It is desirable to clamp or hold the shirt in proper position on the platen so that it will not move between the time of assembly and working engagement of the movable presser thereon, which would cause wrinkles to be pressed into the shirt bosom. This is particularly necessary around the neckband and upper bosom part which is always the most conspicuous part of the shirt while it is being worn, other parts being hidden by a coat, sweater, vest or the like.

The neckband clamping device provided in the present machine comprises a flexible metal band 17 of substantially circular form which, although it is normally maintained in an out-of-the-way inoperative position, as shown by full lines in Fig. 1, may be moved downwardly onto the top 10 of the shirt bosom, as shown in Fig. 2, and may be pulled back solidly against the neckband form 16 to securely clamp the neckband of the shirt to the form and thereby prevent any displacement which might tend to cause wrinkles or creases to be ironed in the shirt.

The operating mechanism of the neckband clamping device comprises a main arm 18 pivotally mounted on a stud 19 and capable of a limited range of clockwise movement from the position shown in Fig. 1, and on its upper end the arm is provided with a pivotal connection 20 to a block 21 for the resilient band 17. The frame 10 is provided with a vertical standard 22 upon which a crank plate 23 is pivotally mounted on a stud 24, and has three pivots 25, 26 and 27. The pivot 25 has a spring connection 28 with the offset finger 29 portion of the main arm 18, while the pivot 26 has a lever 30 connection with the resilient band block 21 at 31 and the third pivot 27 thereon has a yielding connection 32 with the finger 33. The entire clamping device is operated through rotation of the crank plate 23 by a long lever 34 with a ball 35 at its upper end, and by movement of this ball-topped lever into the positions A, B and C, shown in Fig. 1.

Thus, it is merely necessary for the operator to move the ball-topped lever 34 from the position A to the position B after a shirt has been properly located upon the stationary platen 11, whereupon the crank plate 23 moves in a counterclockwise direction upon the stud 24 to move the pivot 25 downwardly and through the compression spring connection 28 move the main arm 18 in a clockwise direction. At the same time the crank plate moves the pivot 26 and interconnected lever 30 to thereby cause the resilient strap frame 17 to move in a clockwise direction about its pivot 20, and by the time the ball-topped lever 34 reaches the position B the resilient band will have moved down onto the shirt bosom and be slightly spaced from the neckband form 16 as shown by section lines in Fig. 1 and by full lines in Fig. 2.

Upon further movement of the ball-topped lever 34 from the position B to the position C resultant counterclockwise movement of the pivot 26 merely moves a lower section 36 of the lever 30 without causing further movement of the upper lever section 37, as permitted by a yielding connection 38 therebetween and as caused by the lower edge of the resilient band 17 engaging the top of the stationary platen 11 and by a strap or finger 39 carried by the block 21 engaging the buttons 40 and 41 on top of the collar form, as shown in Fig. 1. The main purpose of the latter

strap or finger 39 is to take up some of the load imposed upon the resilient band when it is moved in a clockwise direction into engagement with the stationary platen.

In this movement of the ball-topped lever from the position B to the position C the pivot 27 in its continued counterclockwise movement moves a flange 42 of a connecting bolt 43 into engagement with a face 44 of the finger 33, and, because the yielding connection 32 is stronger than the spring 28, it causes the arm 18 to be moved in a counterclockwise direction again and this causes the resilient band 17 to be moved securely against the front face of the neckband form 16 to clamp the neckband of a shirt securely thereto, as shown in Fig. 3.

Preferably, the neckband form is provided with a recessed portion 45 which will accommodate the button on the neckband to thereby minimize the possibility of crushing buttons, and, if desired, the form may be provided with a second recessed portion 46 of slightly less depth to accommodate the built-up portion of the cooperating button-hole without crushing the rim of said buttonhole together unnecessarily.

After the neckband has been thoroughly clamped in this manner and the balance of the shirt front is clamped down onto the platen by other well-known means the movable presser is brought into engagement with the top surface of the stationary platen in order to press the bosom of the shirt. After the shirt bosom has been properly pressed it is merely necessary for the operator to swing the ball-topped lever back into the position A whereupon the resilient band is first moved forwardly then upwardly into its inoperative position by the means hereinbefore described.

When the neckband is clamped in this manner there is no danger of its turning over and being forced down upon the bosom of the shirt to cause needless wrinkling as the movable presser 12 and a rim 47 defining the neckband form clearance aperture 48 moves down into engagement with the shirt bosom in close proximity to the neckband. Particularly, there is no possibility of the shirt front being moved out of position during travel of the movable presser toward the shirt and fixed platen, which would result in improper creasing.

Neckband type shirts have been exceedingly popular and in vogue for many years and the problem of preventing the conspicuous part of the shirt near the neckband from moving and being improperly creased and prevent the neckband from coming into engagement with the shirt bosom during the ironing operation of the latter has heretofore been solved with the use of clamping devices similar to the one hereinbefore described. Until recent years the majority of shirts requiring a neatly ironed bosom were of the neckband type for use with a separated starched collar made from various materials. A later vogue brought in soft collars, but even these were separable and for use with the neckband type of shirt.

The latest and increasing popular vogue with men is the use of shirts with collars attached, because of the convenience obtained by dispensing with the use of a pair of loose collar buttons and, particularly, the greater comfort from this type of shirt.

At first the collars of the collar attached type shirts were protected during the bosom ironing operation by the operator holding back the

- points by hand during the operation of ironing. This was no great hardship or inconvenience when the proportion of collar attached shirts was small in comparison with the number of 5 neckband shirts normally ironed in commercial laundries. However, it proved to be an inconvenience when collar attached shirts were used in increased quantities, for it rendered one of the operator's hands incapable for use in other auxiliary operations during much of the time required 10 to iron a shirt, and created a hazard of crushed fingers because the operator's fingers while holding the collar points would often be very close to the normal path of travel of the movable presser 15 toward the stationary platen.
- Efforts in the past to overcome this hazard and inefficiency resulted in the provision of a pair of pins or projections rising vertically from the neckband form and so arranged that the operator 20 might twist or turn the free ends of the collar in back of the pins previous to the bosom ironing operation. However, these arrangements required considerable manipulation of the collar, for each end had to be handled separately in 25 placing it in back of the pins or other projections and were of necessity slow because the operator had to be careful not to crease or bend the free ends to such an extent as to cause improper wrinkling and creasing. And, with some of these 30 proposals it was also necessary to manually disengage free ends of the collar from the pins after the shirt bosom had been properly ironed which, of course, also added to the time required to iron the shirt.
- 35 These disadvantages are overcome in the present invention by the provision of a safety shield 50, preferably made integral with the neckband resilient strap 17 which extends a substantial height above the latter and which is sufficiently wide to overlap the free ends of any collar attached shirt intended to be ironed in the machine which serves to move the collar ends into a safety zone and maintain them there during the ironing 40 operation.
- 45 Preferably, the safety shield 50 is made slightly concave in form to correspond with the radial front of the neckband form 16 and is made of substantially the same height as the highest attached collars which might be on shirts placed 50 in the machine. Also, it is made just wide enough to overlap the gap between the collar ends, yet not so wide that it impairs the resiliency of the band 17.
- With this invention, it is merely necessary for 55 the operator to place the shirt upon the stationary platen 11, as above described. When this is done, the collar portion has a natural tendency to project upwardly from the neckband, as shown in Fig. 4. However, it may lean forwardly or 60 backwardly somewhat, depending upon the length of the points and the stiffness of the material. Even if they do not initially lean forward, they may do so as a result of the operator straightening the bosom out on the top surface 65 13 of the stationary platen.
- If the movable presser 12 should be brought 70 down on the bosom while the collar ends are projecting forwardly, the latter would be creased down upon the bosom or over the end of the neckband strap 17, unless means are provided to avoid this, or unless the operator holds the collar ends back with her hands while lowering the presser, an extremely dangerous operation.
- With the device of the present invention, after 75 the shirt bosom is laid out upon the top surface 13 of the stationary platen the operator merely swings the ball-topped lever 34 from the position A to the position C whereupon the resilient band 17 and safety shield 50 is moved down and over the top free ends of the collar into the intermediate position B, as shown in Fig. 2, and then to the left across the top of the platen 11 and moves the free drooping ends of the collar rearwardly or to the left into a safety zone so that they will always be out of the path of the rim 47 of the neckband form clearance slot 48, and thereby prevent all likelihood of any portion of the collar being crushed by the movable presser 12.
- This is an especially advantageous feature, for 80 should the collar or any part thereof be crushed or pressed down, usually on the shirt bosom, in an irregular manner it is nearly always necessary to pass the entire shirt through the wash again in order to work out the improperly applied creases in both the bosom and collar.
- 85 Heretofore, it was customary to manually manipulate the free ends of the collar, turning them in back of pins or other projections extending vertically from the top of the neckband 90 form 16. This, however, meant a considerable loss of time and sometimes caused undesirable creases in the collar if the operator was not extremely careful in folding the collar ends in back of the projections, and sometimes the collar ends 95 would become disengaged from the projections and because of inherent resiliency and lack of support would move into the path of the movable presser. All of these disadvantages are overcome with the simple safety shield provided by 100 the present invention, for it spares operators the trouble and time of manually manipulating the free collar ends, placing them in back of projecting bands, lessens the possibility of improperly creasing the collar, and positively moves 105 and insures maintaining the free ends of the collar out of the path of the movable presser.
- 110 After the shirt bosom has been ironed it is merely necessary to throw the ball-topped lever from the position C to the position A again 115 whereupon the resilient neckband clamping strap and the collar safety shield is simultaneously moved back into the intermediate station B and then into the inoperative position shown in Fig. 1, and the operator may remove the shirt 120 to replace it with another which is to be ironed.
- 125 Other variations and modifications may be made within the scope of this invention and portions of the improvements may be used without others.
- 130 Having thus described the invention, what is claimed as new and for which it is desired to obtain Letters-Patent, is:—
1. In a shirt bosom ironing press, the combination of a pair of relatively movable ironing 135 plates; a neckband form on one of said plates, and a clearance for the neckband form in the other plate having a substantially circular rim which is adapted to iron a shirt bosom close to the neckband; means for clamping the neckband of the shirts to said form; and a shield carried by said means and extending a substantial distance above the neckband form when said means is in clamping position, whereby the free ends of the shirt collar will be held from engagement with the circular rim when said plates 140 are relatively moved.
2. In a shirt bosom ironing press, the combination of a pair of relatively movable ironing plates; a neckband form on one of said plates 145
- 150

of relatively small height, and a clearance for the neckband form in the other plate defined by a rim which is adapted to iron a shirt bosom close to the neckband; and a combined strap 5 for clamping the shirt neckband directly to the neckband form and collar safety shield which extends a substantial distance above the neckband form when the strap is in clamping position, whereby the free ends of the shirt collar will be held from engagement with the rim when said plates are relatively moved.

3. In a shirt bosom ironing press, the combination of a pair of relatively movable ironing plates; a neckband form on one of said plates, 15 and a clearance for the neckband form in the other plates comprising a substantially circular rim which is adapted to iron a shirt bosom close to the neckband; and a combined neckband clamping strap, of substantially the same height 20 as the neckband form for clamping a neckband to said form, and a safety shield which extends a substantial distance above the neckband form for moving the free ends of the collar into an area of safety above said collar form and free 25 from engagement with the circular rim when said plates are relatively moved.

4. In a shirt bosom ironing press, the combination of a pair of relatively movable ironing plates; a neckband form on one of said plates of 30 relatively small height, and a clearance for the

neckband form in the other plate defined by a rim forming part of the plate which is adapted to iron the shirt bosom close to the neckband; resilient means of substantially the same height as the neckband form for clamping the neckband 80 of shirts on said form; and a safety shield on said resilient means which extends a substantial distance above the neckband form to overlie collar ends of narrow width so that it will not impair the resiliency of the neckband holding means and will maintain the free ends of the shirt collar 85 from engagement with the rim when said plates are relatively moved.

5. In a shirt bosom ironing press, the combination of a pair of relatively movable ironing plates; 90 a neckband form on one of said plates, and a clearance for the neckband form in the other plate having a substantially circular rim which is adapted to iron a shirt bosom close to the neckband; a strap for clamping the neckband of the 95 shirt on the form; means for moving said strap toward and from said neckband form; and a safety shield on said strap and extending a substantial distance above the neckband form when 100 said strap is in clamping position for positively moving the free ends of the shirt collar into a safety zone overlying said neckband form and out of the path of travel of the circular rim when said strap is moved toward the neckband form.
